a corporation of Delaware

Application November 25, 1931, Serial No. 577,250

6 Claims. (Cl. 62—108.5)

This invention relates to freezing containers especially such as may be used as ice trays for domestic refrigerators.

An object of the invention is to provide an improved form of a molded flexible non-metallic ice tray having a metal support therefor which is simply attached to the molded tray after it is completely molded.

Another object is to provide such a flexible tray having a metal support therefor, which support may itself be flexed or be provided with a hinge movement between its two halves, whereby to facilitate the upward flexing of the central portion of the tray when it is desired to remove its frozen contents.

Further objects and advantages of the present invention will be apparent from the following description, reference being had to the accompanying drawings, wherein a preferred embodiment of one form of the present invention is clearly shown.

In the drawings:

Fig. 1 is a plan view of a tray made according to this invention.

Fig. 2 is a side elevation thereof.

Fig. 3 is an end elevation thereof.

Fig. 4 is a transverse section on line 4—4 of Fig. 1.

Fig. 5 is a section taken on line 5—5 of Fig. 1.

Fig. 6 is a plan view of a modification.

Fig. 7 is in part a section on line 7—7 of Fig. 1 and in part a side elevation of Fig. 1.

Fig. 8 is a bottom view of one end of the tray, looking in direction of arrow 8 of Fig. 7.

Fig. 9 is taken on line 9—9 of Fig. 1.

Fig. 10 is taken on line 10—10 of Fig. 1.

Numeral 10 designates as a whole the molded flexible rubber container or tray which has suitable integral partitions 11 dividing it into ice pockets 12. Tray 10 has two integral lugs 13 projecting at each end thereof and aligned holes 14 extending through the two lugs 13 at each end of the tray. Tray 10 also has a transverse aperture 15 extending across its central bottom portion, best shown in section views 4 and 5. This tray 10 is preferably molded of quite soft and flexible rubber and consequently a stiffening metal support designated as a whole by reference numeral 20, is provided to give said tray proper support when it is filled with water and to facilitate its handling. In the form shown in Figs. 1 to 4, this support 20 comprises four separate fairly rigid metal rods 21, each rod having an inturned end 22 extending into central aperture 15 approximately half way across

the tray. Each rod 21 also is bent inwardly at 23 to pass through the holes 14 in lugs 13 and terminates in an outwardly curved portion 24, to which a suitable hand-grip or handle 25 is applied as described below. These four metal rods 21, shaped as clearly illustrated, may be easily inserted in place in the apertures 14 and 15 after the rubber tray 10 is molded and finished. In this assembling operation the rubber tray is first wet to reduce friction and the 10 curved ends 24 of rods 21 inserted through the holes 14 in lugs 13, the handles 25 of course being absent at this time. The great flexibility of the entire tray 10 readily permits such distortion thereof as may be necessary for so inserting rods 21. The inturned ends 22 of rods 21 are next inserted within the central aperture 15, which is preferably just large enough to snugly receive the ends 22 lying side by side as clearly shown in Fig. 5. Now having so attached the four rods 21 to the rubber tray 10 in the manner described, the soft flexible molded rubber handles 25 are next applied to the curved projecting ends 24 of rods 21. The easy distorsibility of both the handles 25 and the entire tray 10 is relied upon for so applying handles 25. To do this, preferably the tray 10 is substantially folded upon itself about its longitudinal center line in order to bring the curved ends 24 into approximate parallelism. These 20 ends 24 are then inserted into the corresponding holes 26 in handle 25 which at the same time is bent or folded about its center line to bring said holes 26 into approximate parallelism. The curved ends 24 of the metal rods 21 may 30 then be forced into holes 26 by hand, the rubber of course being wet to facilitate the slipping of rubber on metal.

In operation, to remove the frozen contents from the tray, the two handles 25 are grasped 40 one in each hand and by a bending action on the tray about its transverse center line the central portion thereof may be easily flexed or distorted upwardly sufficiently to loosen all the ice cubes and even to force the cubes near the 45 center of the tray entirely from their pockets. During this bending action the two metal rods 21 fastened to each handle 25 move together as half of the supporting metal frame 20. Such two halves of the frame have an easy hinge 50 movement relative to each other since the inturned ends 22 lying in aperture 15 are not connected but readily slide upon one another. The tray is also capable of being similarly flexed about its longitudinal center line since the two 55

rods 21 on one side of the tray are not connected to the two rods 21 on the other side and since the handles 25 as well as the soft rubber tray 10 are easily distorted about any axis. Thus 5 the metal frame 20 gives all necessary support for the rubber tray but at the same time it is divided into four relatively movable quarters so that the entire unit may be readily flexed in most any desired manner to facilitate the removal of the frozen contents.

In the form of the invention shown in Figs. 6 to 10, the one-piece molded rubber tray 40 has two integral apertured lugs 41 and a central apertured lug 42 at each end of the tray. The 15 supporting metal frame 45 comprises two resilient metal rods 46, each having inturned ends 47 which project through the holes in the lugs 41, and the bent extremities 48 of rods 46 are rigidly secured to the metal handles 50 by any 20 suitable means, such as by the small metal clamps 49 fixed to the handles 50 by screws 51. Handles 50 are also attached to the central rubber lugs 42 respectively by means of the pin 52 which passes through a hole in lug 42 and 25 through two ears 53 on each side thereof. The two metal handles 50 are thus securely but flexibly attached to the two ends of the rubber tray 40 and form part of the supporting frame 45. The two resilient side rods 46 are connected 30 together across the bottom of the center of the tray by a metal strap 55. Strap 55 preferably lies snugly up within a groove molded in the bottom of the tray so it will lie flush with the bottom surface thereof.

In operation, to remove the frozen contents 35 of the tray, the two handles 50 are grasped, one in each hand, and the entire tray bent upward at its central portion similarly to the method of operation of the first tray described. The 40 side rods 46 are quite resilient and so permit such upward bending of the central portion or, to look at it in another way, the downward bending of the end portions of the tray.

While the form of embodiment of the present 45 invention as herein disclosed, constitutes a preferred form, it is to be understood that other forms might be adopted, all coming within the scope of the claims which follow.

What is claimed is as follows:

1. A freezing tray comprising: a flexible rubber container having partitions therein to form ice pockets, and a metal support attached to said container to prevent undue flexing thereof when filled with water, said support being attached to said flexible container only at its two opposed end portions and its central portion

whereby to facilitate the manual flexing of said container to remove the frozen contents therefrom.

2. A freezing tray comprising: a flexible rubber container having partitions therein to form ice pockets, and a metal support attached to said container to prevent undue flexing thereof when filled with water, said support comprising metal rods extending exterior of but adjacent to two opposed sides of said container and having portions supporting said container at its two end portions and its central portion whereby to facilitate its manual flexing to remove its frozen contents.

3. A freezing tray comprising: a flexible rubber container having partitions therein to form ice pockets, and a metal support attached to said container to prevent undue flexing thereof when filled with water, said support comprising metal rods extending exterior of but adjacent to two opposed sides of said container and having portions supporting said container only at its two upper end portions and its central portion.

4. In combination, a molded flexible rubber freezing tray having integral apertured lugs at its two ends, and a metal support for said flexible tray comprising metal rods extending exterior of but adjacent to the opposed sides of said tray and having inwardly turned end portions fitting within said apertured lugs whereby to support the two ends of said rubber tray, said rods also having means supporting the bottom central portion of said tray.

5. In combination, a molded flexible rubber freezing tray having integral apertured lugs at its two ends, and a metal support for said flexible tray comprising metal rods extending exterior of but adjacent to the opposed sides of said tray and having inwardly turned end portions fitting within said apertured lugs whereby to support the two ends of said rubber tray, said rods also having means underlying and supporting the bottom central portion of said tray.

6. In combination, a molded flexible rubber freezing tray and a metal support therefor attached thereto at its two upper end portions and its lower central portion, said combined rubber tray and metal support being capable of a substantial endwise bending movement, whereby to facilitate the upward flexing of the central portion of said tray.

HARVEY D. GEYER.

FREDERICK W. SAMPSON.
